MEDICAL BANDAGE

Julius Slomowitz, Newark, N. J., and Mario Del Conte, Brooklyn, N. Y.

Application June 1, 1950, Serial No. 165,522.

4 Claims. (Cl. 128—268)

1

This invention relates generally to adhesive medical bandages. It pertains particularly to a type of adhesive bandage that serves not only as a protective covering for wounds, but also as a source of medicine.

The invention represents an improvement over those bandages wherein the medicament is originally impregnated in a gauze pad. In the present invention the medium of medication is not originally impregnated in a gauze pad, but is contained in a small blister embedded in absorbent material. When its use is desired the blister is gently pressed or squeezed causing it to burst. The contents thereupon oozes out and impregnates the absorbent gauze material.

There are many obvious advantages to a bandage of this kind. In the blister there is always contained a fresh supply of medicine. The medicament is sealed within the blister. There is no danger of it becoming stale or drying out as would occur in those types of bandages where the medicament is impregnated in the bandage for use at some later date.

The general object of this invention is a medical bandage containing a readily breakable blister in which there is contained a supply of medicament.

Another object of the invention is an adhesive medical bandage containing a ready source of medicine for topical application.

A further object of the invention is an adhesive bandage carrying a fresh supply of medicine at all times, and which is particularly suitable for use with boils, carbuncles, corns, and the like.

Another object of the invention is a readily breakable blister serving as a source of medicine in the treatment of sores, wounds, bruises, and the like.

These, as well as other objects and advantages of this invention, will become apparent as this specification unfolds in greater detail, and as it is read in conjunction with the accompanying drawings wherein a preferred form of the invention as well as several modifications are illustrated.

In the drawings,

Fig. 1 is a perspective view of an adhesive bandage embodying the invention with some of the elements in raised position to better reveal its construction;

Fig. 2 is the same as the view in Fig. 1, but with some of the elements removed to better reveal the basic structure;

Fig. 3 represents an enlarged longitudinal section through the center of Fig. 1, on line 3—3 of

2

Fig. 1 with the raised elements shown in Fig. 1 in normal position.

Fig. 4 is an enlarged view of the blister itself;

Fig. 5 is a cross section of the blister;

Fig. 6 is a perspective view of a modified form of the invention;

Fig. 7 is a plan view of another form that the invention may take;

Fig. 8 is a longitudinal cross section of Fig. 7 through the center;

Fig. 9 is a cross section longitudinally through the center of a form of the invention similar to that form contained in Fig. 7 but with an added feature contained in the blister; and

15 Figs. 10, 11, and 12 represent further forms of the invention.

Referring to the drawings, particularly to Figs. 1 to 5, inclusive there is disclosed an adhesive bandage containing a blister carrying a supply of medicine. The bandage comprises a strip of adhesive cloth or tape 1. The adhesive substance covers the inner or body contacting surface 2 of the strip. Adhering to the adhesive surface 2 is a substantially flat pad 3 consisting of a length of absorbent gauze material having several layers of thickness. Pad 3 is secured to the adhesive strip in such manner that the free end 4 of the bottom layer as well as an extended portion 5 of the top layer are in contact with the adhesive substance of strip 1, as appears in Fig. 2. By securing the gauze in this manner to the adhesive cloth there is no likelihood of the free ends 4 and 5 of the pad becoming loose and causing the pad to unravel. Also, by rolling the gauze material in a pad a series of folds or pockets are formed between the several layers of gauze. Between these folds, preferably the center one, there is embedded a small, substantially flat blister 6 carrying a fresh supply of medicine 7.

40 The medicine carrier is called a blister, as that term best describes its nature. It is intended to be a container of a medicinal substance with a thin readily breakable skin covering or wall 8. Upon squeezing or the application of slight pressure, the substance within the blister is intended to break through the tender wall of the blister and impregnate the surrounding gauze material in which it is embedded.

45 The thin wall of the blister is intended to be of a soft tender material. The blister is fashioned preferably of polyethylene plastic material, which is soft and particularly adapted for the uses intended. The blister may, however, well be made of other materials suitable for the purposes intended. The blister is substantially flat and

preferably contains a medicament, such as iodine, mercurochrome, or other antiseptic suitable for application with everyday scratches, bruises and hurts. Blisters may be made up to carry other medicaments, such as, zinc oxide, petroleum jelly, sulfa compounds, and other ointments, salves, and powders.

An additional layer of gauze 10 may be laid longitudinally over the pad with its extended ends 11 secured in the adhesive substance of the tape 1. This will effectively confine the blister within the pad and prevent its contents, when the blister is broken, from oozing out between the layers of the gauze pad. If desired, the several layers of the gauze pad may be secured together by one or more stitches through the pad.

The gauze pad as well as the adhesive portions of tape 1 extending out on either side of the pad are covered by a readily removable material, such as crinoline. This backing material serves as a protective covering and facilitates handling of the bandage, particularly the adhesive portions. This crinoline material may be a single strip running the full length of the bandage, or, as shown in Fig. 1, it may comprise two strips 12, one for each end of the bandage. Each strip 12 is adhered to the adhesive side of the tape 1 and extends a little beyond the middle of the pad, so that both strips will overlap each other on the pad 3. The overlapping portions of crinoline are free and may be readily lifted for removal when the bandage is to be used as illustrated in Fig. 1.

Having described the invention in detail, its many advantage now appear quite apparent. It can readily be seen how these blisters may be made up to carry medical substances of various types, particularly those that are required for everyday use with bruises, cuts, burns, scratches, minor operations, etc. The blisters may contain such medicaments as iodine, mercurochrome, vaseline, zinc oxide, carbolic salve, ichthyol, sulfa, and others. The contents of the blister are sealed in and will remain fresh at all times until ready for use without drying out, or becoming stale or contaminated.

The bandage is particularly adaptable for emergency use. All one need do when using the bandage is to squeeze the blister slightly to allow it to burst and its contents to ooze out into the absorbent gauze pad. The crinoline is then removed and the bandage is applied to the affected area of the body. Where the bandage is to be applied to the fingers, pressure exerted on the tape while applying will be sufficient to cause the blister to burst and emit its contents.

The invention may take many forms, some of which are added here below.

The embodiment in Fig. 6 is an economical form adaptable for ready use with a variety of medicine contained blisters. In this form a blister 13 containing a medicament is adhered to the center of the adhesive side of a strip of tape 14. A pad 15 of absorbent gauze is positioned over the blister and adhered to the tape. This is a quickly put together form, economical to manufacture, and provides fair results. In this form tapes, blisters, and pads may be made up separately for quick and ready assembly when needed. Crinoline backing may also be added to this form as in Fig. 1.

In Fig. 7 is disclosed another form of the invention that is particularly adaptable for use with boils, carbuncles, and the like. In this form a strip of adhesive tape 17 has adhered to its center a blister 18 containing a suitable boil ointment,

or other medicament. The blister is also preferably made of polyethylene plastic material, or of some other material that is suitable for the use intended. Polyethylene is preferred because of its soft, non irritating nature. In this form it is to be noted that the blister is in the nature of a container having a base 19 and a circular wall 20. The circular wall encompasses a core of medicament 21. The core is sealed in by a thin skin or wall 22. Because this form is of particular use for boils, carbuncles, and the like, the top surface 23 of the blister is slightly concaved. Slight pressure on the circular wall will break the thin seal 22 and cause the medicament to ooze out. In this form the head of a boil where the medication is actually needed is permitted to extend into the core of medicament 21. The circular wall and base of the blister are thickened to maintain the form of the blister and to serve as a protective support for the boil against rubbing and irritation of clothing. The blister may be covered with a layer of gauze, but the polyethylene material of which the blister is constructed is of such a soft and non-irritating nature that the gauze pad can be dispensed with. The purpose of this form of the invention is primarily to keep the head of a boil lodged in the medication until it is "ripe." This form is also of value when used in the treatment of corns.

30 In cases of those boils and other infectious sores where it is desired that the wound be kept open to promote drainage, a form of the invention as appears in Fig. 9 may be used to advantage. This form is in all respects similar to that of Fig. 7 except that a small tampon 24 of absorbent gauze is contained in the core of the blister engulfed in a suitable ointment 25. In this form when the blister is squeezed the thin covering seal 26 breaks and causes the tampon to protrude slightly with the medicament. The blister is then taped over the wound. The tampon surrounded by ointment will protrude slightly into the open wound to effect a continued opening of the wound and to promote drainage.

45 A blister 27, such as illustrated in Fig. 10, containing a suitable medicament according to the use intended may be embedded in a sterile absorbent gauze pad 28 illustrated in Fig. 10. A pad of this nature finds many uses for topical application as a dressing for minor operations, burns, sores, and other afflictions.

There are other uses in which the blister shown in Fig. 4 finds use, such as in a swab or tampon. In Fig. 11 there is shown a swab stick 29 with a 55 tip of absorbent gauze material at one end. A blister 30 containing a supply of medicament is embedded in the gauze tip 31. Slight bending or squeezing of tip 31 will break the blister and allow its contents to ooze out and soak into the surrounding gauze.

In Fig. 12 there is shown a tampon 32 suitable for insertion into the cavities of the body, such as the nasal passages and the like. Contained within the tampon is a blister 33 of medicine, 65 which also can be broken by squeezing when its use is desired. The contents of the broken blister will ooze out into the surrounding tampon material.

Having described the invention in its preferred form as well as in several other forms, it is intended to claim all that may be reasonably included within the spirit and scope of the invention as defined by the appended claims.

We claim:

1. A blister for use with protuberant sores com-

prising a thickened circular wall and base of soft non irritating plastic material, a core of a medicament, and a thin surface wall sealing said medicament within the confines of the circular wall, said surface wall being readily breakable upon squeezing the circular wall of the blister, and the surface wall of the blister being slightly concaved to accommodate a protuberant sore, said medicament being issuable upon the breaking of the thin surface wall.

2. A blister of soft non irritating plastic material for use with protuberant sores and open wounds, comprising in combination a thickened circular wall and a base for such, a core of medicament encompassed by said circular wall, a tampon engulfed in the medicament, a thin surface wall sealing said medicament and tampon within the confines of said circular wall, said surface wall being readily breakable upon squeezing of the circular wall, said tampon serving as an insert for an open wound, and said tampon and medicament being issuable upon breaking of the surface wall.

3. The combination with a strip of adhesive tape of a container of soft non irritating plastic material for use with protuberant sores, said container being fixed to the surface of the tape and having a thickened base and a circular wall, a core of a medicament encompassed within the confines of said circular wall, and a surface covering sealing said core in, said surface covering being slightly concaved and readily breakable upon squeezing.

4. The combination with a strip of adhesive tape of a container of soft non irritating plastic material for use with protuberant sores and open wounds, said container being fixed to the surface

of the tape and comprising a thickened base and a circular wall, a core of medicament encompassed within the confines of the circular wall, a tampon engulfed in the medicament, a thin surface wall sealing said medicament and tampon within the container, said surface wall being readily breakable upon squeezing of the circular wall whereby the tampon and medicament tend to issue forth, said tampon serving as an insert and means for drainage for an open wound.
